Inventor:-

Benjamin Singer
By Ralph Raesch
Att'y.

UNITED STATES PATENT OFFICE.

BENJAMIN SINGER, OF ST. LOUIS, MISSOURI.

LOCK FOR DOORS, WINDOWS, AND THE LIKE.

1,399,897.

Specification of Letters Patent. Patented Dec. 13, 1921.

Application filed June 28, 1920. Serial No. 392,249.

To all whom it may concern:

Be it known that I, BENJAMIN SINGER, a subject of Russia, residing at the city of St. Louis, State of Missouri, have invented a certain new and useful Improvement in Locks for Doors, Windows, and the like, of which the following is a specification, reference being had to the accompanying drawing, forming a part thereof.

This invention relates to a certain new and useful improvement in locks for doors, windows, and the like.

The chief object of my present invention is to provide a lock comprising a pair of companion members which will efficiently coöperate when upon a door and its jamb to securely hold or lock the door from being sprung or forced open and when upon a window to provide a barrier for preventing the usual pivoted window-lock from being forced from the outside.

Another object of my present invention is to provide a lock of the type stated which may be readily and economically manufactured, and which may be conveniently fixed upon the window or door.

With the above and further objects in view, my invention resides in the novel features of form, construction, arrangement, and combination of parts hereinafter described and afterward pointed out in the claims.

In the accompanying drawing,

Figure 1 is an elevational view of one of the members of the door-lock;

Fig. 2 is a similar view, partly broken away and in section, of the companion member of the door-lock;

Fig. 3 is a fragmental elevational view of a door and its jamb equipped with a lock embodying my invention;

Fig. 4 is a transverse sectional view of the parts seen in Fig. 3;

Fig. 5 is a perspective view of one of the members of the window-lock;

Fig. 6 is a similar view of the companion member of the window-lock; and

Fig. 7 is a fragmental transverse sectional view of a pair of window-sashes equipped with a window-lock embodying my invention.

Referring more in detail to the said drawing, in which like reference-characters refer to like parts throughout the several views, and having reference especially to Figs. 1, 2,

3, and 4 of the drawing, the door-lock proper includes a pair of companion or coöperating members A and B.

The member A, which I may descriptively term the male member of the lock, comprises a body-portion in the form of a suitably elongated plate 1 depressed inwardly or rearwardly within its length to provide a so-called cavity or chamber, as at 2. Integral with a side edge of plate 1 at its depression 60 or cavity 2, as best seen in Fig. 1, is a tongue or extension 3, which is bent over to provide or form a hook lying within the cavity or depression 2, the outer face of hook 3 being preferably flush with the outer face of the portion of plate 1 to each side of the cavity 2, and the hook being spaced at its inner face from the outer face of the cavity-forming portion of the plate. Both the hook 3 and the portion 2 of plate 1 are suitably cut 65 away transversely to provide registering apertures 4—4, for purposes shortly appearing. Integral with the opposite side edge of, and disposed at right angles to, plate 1, as also best seen in Fig. 1, is a rearwardly presented strengthening flange 5.

The companion or female member B of the lock similarly comprises a body-portion in the form of a suitably elongated plate 6 correspondingly depressed outwardly or forwardly within its length, as at 7, for coöperation with the cavity 2 and hook 3 of member A, the depressed portion 7 of plate 6 being likewise cut away to provide apertures 8 adapted for registration with the apertures 90 4 of plate 1 and hook 3.

Plate 6 is similarly provided at one side edge with a rearwardly presented right-angular strengthening flange 9.

In use or operation, the member A is preferably fixed to and upon the jamb J, as best seen in Figs. 3 and 4, as by means of suitable fastening screws projected into the jamb through suitable openings 10—10 provided for the purpose in plate 1 and its flange 5. The jamb is preferably cut away or recessed 95 to provide a pocket in which the member A is seated with the outer face of its flange 5 substantially flush with the outer side face of the jamb and with the outer face of plate 1 somewhat below the plane of the outer end face of the jamb. The member B is similarly fixed in coöperative position upon the door D, as also seen in Figs. 3 and 4, and when so fixed upon the door the depressed 100 105 110

portion 7 of the plate 6 forms or provides with the end face of the door a pocket for receiving and accommodating the hook 3 of companion member A. The members A and B being so fixed in operative position upon the door and jamb, it will be seen that the depressed portion 7 of plate 6 is accommodated and received by the cavity 2 of plate A with hook 3 fitting in the pocket formed 10 as described by the plate 6 and the door D. With the members A and B so engaging, it will be evident that the two plates or members of the lock efficiently coöperate or coact to securely hold the door from being 15 sprung or forced open by a "jimmy" or other such tool. Although it will be evident that the lock-members A and B may be fitted at any desired or convenient coöperating location upon the door and jamb, the said members 20 are preferably located upon the door and jamb to coöperate with the usual door lock and latch, in which event, as here shown, the registering apertures 4 and 8 of the members A and B readily permit the operation 25 of the usual door-latch 11 and the projection of the usual locking bolt 12 into and from door-locking position.

Referring now more especially to Figs. 5, 6 and 7, wherein the modified form of the lock shown is designed more particularly for use in connection with window sashes, the lock similarly comprises a pair of coöperating or companion members, the member A' being the male member and the member B' being the female member of the lock.

Member A' likewise comprises a body-portion in the form of an elongated plate 13 formed integrally at one side edge with an extension or hook-portion 14, which is disposed at right angles, and somewhat reduced in length relatively, to the plate 13.

The member B' also comprises a body-portion in the form of an elongated pocket-providing plate 15, which is provided preferably integrally at one side edge with an extension 16, which is first bent downwardly to extend at right angles to the plate 15 and is then bent or folded upwardly upon itself, as at 17, the portion 17 being closely clenched 40 in contact with the portion 16 at the ends thereof and being centrally spaced from the portion 16 to provide a pocket 18 of dimensions adapted to receive and accommodate the extension or hook 14 of member A'.

In use or operation, the member A' is fitted and fixed, as by securing screws 19—19 projected through plate 13 and its hook-flange 14, upon the upper bar 20 of the lower window-sash. The member B', as best seen in Fig. 6, 50 is fitted and fixed, as by securing screws 21, in coöperating position relatively to the member A' upon the upper face of the lower bar 22 of the upper sash of the window, the bar 22 being preferably cut away or recessed 60 to neatly accommodate the member B', as

seen in Fig. 7. With the members A' and B' so fitted and fixed in coöperating position upon the window sashes, it will be seen that, when the window-sashes are in closed position, the hook or flange-portion 14 of member A' will fit within the pocket 18 of member B'. For accommodating the securing screw 19 projected through the flange 14 of member A', the portion 17 of member B' is cut away, as at 23.

Mounted upon the members A' and B' are the usual coöperating members E and F of a standard window lock, as seen in Fig. 7, and it will now be evident that, when the sashes are in closed position, the coöperating members A' and B' of the lock provide or form a barrier to the locking members E and F, preventing access to such locking members for forcing or springing the same from the outside of the window. When the lock-member E is in open position, the window sashes may be raised and lowered in the usual manner.

I am aware that changes in the form, construction, arrangement, and combination of the several parts of my lock may be made and substituted for those herein shown and described without departing from the nature and principle of my invention.

Having thus described my invention, what I claim and desire to secure by Letters Patent is:

1. A lock of the kind described comprising a first plate adapted for location upon an end face of a door, the plate being depressed within its length to form with the door a pocket, in combination with a second plate adapted for location upon an end face of the door-jamb, the second plate being also depressed within its length to provide a cavity for coöperation with the depressed portion of the first plate, and a hook integral with one side edge of the second plate and adapted to fit within said pocket when the door is closed, the hook lying within the depression of the second plate and its outer face being flush with the outer face of the second plate to each side of said depression.

2. A lock of the kind described comprising a first plate adapted for location upon an end face of a door, the plate being depressed within its length to form with the door a pocket, in combination with a second plate adapted for location upon an end face of the door-jamb, the second plate being also depressed within its length to provide a cavity for coöperation with the depressed portion of the first plate, and a hook integral with one side edge of the second plate and adapted to fit within said pocket when the door is closed, the hook lying within the depression of the second plate and its outer face being flush with the outer face of the second plate to each side of said depression and the hook and the depressed

- portion of the first plate being provided with apertures adapted for registration when the door is closed to accommodate the locking bolt of the door.
- 5 3. A lock of the kind described comprising a first plate adapted for location upon an end face of a door, the plate being depressed within its length to form with the door a pocket, in combination with a second plate adapted for location upon an end face of the door-jamb, the second plate being also depressed within its length to provide a cavity for coöperation with the depressed portion 10 of the first plate, and a hook integral with

one side edge of the second plate and adapted to fit within said pocket when the door is closed, the hook lying within the depression of the second plate and its outer face being flush with the outer face of the second plate to each side of said depression, and the hook 20 and the depressed portions of the first and second plates being provided with apertures adapted for registration when the door is closed to accommodate the locking bolt of the door.

25 In testimony whereof, I have signed my name to this specification.

BENJAMIN SINGER.
